Des. 205,710
Patented Sept. 13, 1966

205,710

CHRISTMAS ORNAMENT

James F. Kirchenbauer, 1187 E. 169th St.,
Cleveland, Ohio

Filed June 21, 1965, Ser. No. 85,826

Term of patent 14 years

(Cl. D29—1)

FIG. 1 is a front perspective view of a Christmas ornament showing my new design;

FIG. 2 is another perspective view taken from one side thereof; and

FIG. 3 is a top plan view thereof.

I claim:

The ornamental design for a Christmas ornament, substantially as shown.
